LAUNDRY SORTER

John J. Hamilton, Cincinnati, Ohio, assignor to Hamilton Cosco, Inc., Columbus, Ind., a corporation of Indiana

Filed Apr. 12, 1968, Ser. No. 11,438

Term of patent 14 years

U.S. Cl. D49—8.2
Int. Cl. D7—06

Fig. 1

Fig. 2

FIG. 1 is a perspective view of a laundry sorter showing my new design, the other sides being substantially the same in appearance.

FIG. 2 is a top plan view thereof.

I claim:

The ornamental design for a laundry sorter, as shown and described.
